JOURNAL LUBRICATOR

Edward C. Jeffers, Park Ridge, and Martin C. Jeffers, Wilmette, Ill.

Application July 20, 1956, Serial No. 599,096

9 Claims. (Cl. 308—88)

The present invention relates to journal lubricating devices, and in particular to such devices having novel means for properly locating and anchoring the elements thereof in the journal box.

It is a principal object of the present invention to provide a new and improved journal lubricator which is readily installed in a journal box and, when installed, properly locates the elements thereof with respect to the journal, and insures an even distribution and application of lubricant from the well to the journal under all operating conditions.

Another object is to provide a novel journal lubricator wherein the lubricating element resists disintegration under operating temperatures up to 400° F. and prevents journal seizure in temperatures as low as —60° F.

Another object is to provide a novel journal lubricator comprising an assembly of a lubricating pad in contact with the journal, a fillet seal and lubricator, and a journal box lid seal, with each element properly located with respect to the journal box and the journal.

Another object is to provide a novel journal lubricator which may be anchored in the journal box by a single bolt.

A further object is to provide a novel journal lubricator which, when anchored, firmly presses a fillet seal and lubricator against the inner wall of the journal box and holds a lid seal in position to be engaged by the journal box lid.

Still another object is to provide a new and improved journal lubricator assembly which has a visual oil level gauge incorporated therein.

Still another object of the invention is to provide a novel journal lubricator which is easily removed for inspection and repositioning or replacement, if necessary.

Other objects and advantages will become apparent from the following description taken in conjunction with the accompanying drawing, wherein:

Fig. 1 is a perspective view of a journal box and journal with portions of the box cut away to show the journal lubricator of the present invention properly installed;

Fig. 2 is a longitudinal section through the journal box and lubricator, but showing the pad of the lubricator which is in engagement with the journal in full lines, and may be considered as taken along the line 2—2 of Fig. 3, looking in the direction of the arrows;

Fig. 3 is a transverse section and may be considered as being taken substantially along the line 3—3 of Fig. 2, looking in the direction of the arrows;

Fig. 4 is a section taken substantially along the line 4—4 of Fig. 2, looking in the direction of the arrows, and showing the mounting of the journal box lid seal; and

Fig. 5 is a detail sectional view showing the connection between the mounting strip and the fillet seal and lubricator.

In the drawing, the reference character 10 indicates in its entirety the novel journal lubricator of the present invention, which is located in a journal box 12, through

the inner walls 14 and 16 of which extends a journal 18. The journal box has the conventional access opening 20 at its outer side or face, which is closed by a conventional spring biased lid 22.

5 The journal lubricator 10 includes a journal lubricating section 24, a fillet seal and lubricating section 26, and a lid seal section 28.

The journal lubricating section 24 comprises a sheet of porous fibrous material 30 which preferably is a

10 silicone impregnated wool felt. Other materials may be used, but it has been found that the silicone impregnated felt is especially desirable inasmuch as it reduces the friction between the felt and the journal, effecting a reduction in operating temperatures and an increase in

15 the resistance of the felt to disintegration from heat up to approximately 400° F., and precludes the possibility of journal seizure in temperatures as low as —60° F. The felt sheet is folded or bent to provide a base segment 32, and a journal lubricating segment 34 which extends

20 upwardly and at an acute angle from the base section 32, the latter being positioned in the lubricant well 31 of the journal box. At its upper and outer end the lubricating section 34 is bent back upon itself to provide a spacing pad, or the like, 36, the function of which will 25 become apparent hereinafter.

The journal lubricating segment 34 is biased firmly into contact with the journal 18 by a plurality of resilient biasing members 38. Each of the members 38 includes a base

30 leg 40, a lubricator segment leg 42, and an acute angle member 44. The base leg 40 is secured to the angle 44 by a pair of rivets 46, and the leg 42 is similarly secured to the angle by a pair of rivets 48. The angle is relatively rigid as compared with the legs 40 and 42, which may be made of spring steel. Each leg 40 is secured to the base

35 segment by a single heavy wire clip or staple 50, and similarly each leg 42 is secured to the spacer pad 36 of the lubricator segment 34 by a single wire clip or staple 52. In this manner the plurality of resilient biasing members 38 are secured, respectively, to the base segment

40 32 and to the lubricator segment 34, and tend to separate them, thereby firmly pressing the lubricator segment 34 against the journal 18. The spacer pad 36 insures that the journal is contacted over a substantial portion of its circumference as shown in Fig. 3.

45 Underlying the legs 40, and overlying the base segment 32 of the porous sheet 30, is a spring metal mounting strip 54 which extends from the inner end of the base segment 32 and projects forwardly of the lubricator segment 34 toward the front or open end of the journal

50 box 12. The strip 54 is secured as by rivets 56 to each leg 40 of the resilient elements 38, there being two of the rivets 56 for each leg 40, to prevent angular offsetting of the strip and the leg 40. At its forward end the mounting strip 54 overlies a T-shaped projection 58 of the base segment 32. At its inner end the strip 54 is secured by the rivets 40, not only to the inner of the legs 40, but also to an angle 58 having an upstanding

55 flange 60 which is secured by pairs of rivets 62 to diagonally extending fingers 64, the angle between the fingers being approximately 90°.

60 The fillet lubricator and seal 26 comprises an arcuate pad 66 formed of the same material as the sheet 30. The pad 66 is faced at the side thereof which bears against the journal box wall 16 and against the fillet 68 between the journal 18 and the axle shoulder 70, with a wear

65 resisting sheet 72 made of a material not attacked by lubricant, such as neoprene. The pad 66 is secured to the flange 60 and to the outer ends of the fingers 64 by a plurality of rivets 74.

70 Between the inner journal box walls 14 and 16 is a dust guard and oil seal 75 which, together with the fillet seal

and lubricator 26, prevents the escape of lubricant from the well 31 of the journal box and the entry of dirt along the shoulder portion 70 of the axle.

The T-shaped projection 58 from the base segment 32 of the sheet 30 preferably is integral with the sheet but, if desired, may be made separate. It has at its outer end a cross pad 76 which, when the lubricator is properly positioned in the journal box, extends the width of the journal box as seen in Fig. 4, and its outer lip, as seen in Fig. 2, is at the edge of the inclined front well wall 27 to form the lid seal 28. A transverse strip 78 overlies the cross bar pad 76 and is secured thereto by a plurality of rivets 80 and by a heavy wire clip 82. The wire clip 82 also passes through, and fastens to the pad portion 76, a relatively heavy gauge metal anchor plate 84 which is secured to the strip 78 by rivets 86, and to the outer end of the mounting strip 54 by a plurality of rivets 88. The plate 84 is substantially stiffer than the spring steel strips 54 and 78 so as to resist bending.

The anchor plate 84 has a medial longitudinal slot 90 formed therein which coincides with a similar slot 92 in the cross bar pad 76. These slots afford longitudinal adjustment of the lubricator 10 and accommodate a carriage bolt 94 which is passed therethrough and through a specially drilled hole 96 in the journal box wall 77 adjacent the opening 20. The carriage bolt also passes through a synthetic lubricant resisting rubber washer 97 to assist in sealing the drilled hole in the journal wall 77 against the leakage of lubricant.

At the inside of the journal box the bolt 94 is fitted with a tempered spring steel periphery dome washer 100, and at its outer end is fitted with a lock nut 98. When the nut is drawn tight small projecting teeth around the hole in the dome washer 100 will embed themselves in underside of the the bolt head, and the dome washer 100 in cooperation with the tightened lock nut 98 will exert a back pressure on the anchor plate 84 so that there is a firm and tight anchorage of the lubricating device 10, and no amount of car vibration can loosen its mounting in the journal box.

It should be noted that when the journal lubricator 10 is properly anchored, the base segment 32 is in the well 31 of the journal box 12, the fillet lubricator and seal 26 is pressed firmly against the wall 16, and the journal lubricator 34 contacts the journal 18.

A visual lubricant level gauge 102 is secured as by a heavy wire clip or staple 104, to the stem portion of the T-shaped projection 58 at the outer end of the base segment 32. This visual oil level gauge 102 preferably is made of the same material as the sheet 30. It is desired that the oil in the journal box will be maintained at a level just to cover the visual gauge, although, with the journal lubricating device of the present invention, if there is any free oil in the journal box it will be fed to the journal lubricating segment 34 and thus insure positive lubrication of the journal under all conditions of operation.

The synthetic rubber washer 97 has an additional use. Should it ever be necessary to remove the lubricating device 10 and not replace it with one of the same design, the bolt 94 is secured in the hole 96 in the well wall 77 with the washer 97 between the bolt head and wall to seal the hole and prevent leakage of oil from the well 31.

The journal lubricating device of the present invention is installed in a journal box by compressing the journal lubricating segment 34 toward the base segment 32 so that the two can be slipped under the outer flange on the journal 18. The fillet seal 26 is tipped under the flange and the journal lubricator assembly 10 is then, with a steady pressure, forced under the flange until the fillet seal comes to rest against the wall 16. In this position the lubricator segment 34 will underlie the journal 18 and its outer edge will be within the flange at the outer end of the journal. The lid seal pad 76 will have its outer edge at the outer edge of the lip forming the bottom of

the well, and the hole 96, if it has not already been drilled in the journal box well wall 77, should be drilled at this time. The carriage bolt 94 fitted with the dome washer 100 and sealing washer 97 is inserted through the hole 96 and, when an adequate pressure has been applied to the seal 26, the lock nut 98 is tightened. The flexible spring metal mounting strip 54 places pressure upon the fillet lubricator and seal 26 to seat the latter (Fig. 2), thereby to prevent oil from splashing out of the inner end of the journal box.

The lubricating device 10 may be readily removed from the journal box by removing the carriage bolt 94, depressing the journal lubricator segment 34 so as to clear the flange, and pulling the end of the lubricator pad so that the assembly slides under the flange on the journal. The lubricating device 10 may be relocated in the journal box or replaced as hereinbefore described.

From the foregoing it will be appreciated that the objectives which are claimed for the present invention are attained by this structure.

While a preferred embodiment of the journal lubricating device constituting this invention has been shown and described, it will be apparent that numerous modifications and variations thereof may be made without departing from the underlying principles of the invention. It is therefore desired, by the following claims, to include within the scope of the invention all such variations and modifications by which substantially the results of the invention may be obtained through the use of substantially the same or equivalent means.

What is claimed as new and desired to be secured by United States Letters Patent is:

1. A journal lubricating device adapted to be mounted in a journal box through an end wall of which extends a journal and which has a well below the journal for holding a liquid lubricant, an access opening through the end wall, and a lid closing the opening, comprising, a sheet of porous fibrous material having a base segment locatable in the journal well and an angularly upwardly extending lubricating segment pressable against the journal, a journal box lid seal connected to and integral with said base segment, mounting means overlying said base segment and said lid seal, means adapted to secure said mounting means where it overlies said lid seal to the journal box thereby to anchor the lubricating device in journal lubricating and lid sealing position, and resilient means secured to said mounting means and adapted to bias said lubricating segment against the journal.

2. A journal lubricating device adapted to be mounted in a journal box through an end wall of which extends a journal and which has a well below the journal for holding a liquid lubricant, an access opening opposite the end wall, and a lid closing the opening, comprising, a sheet of porous fibrous material folded to provide a base segment locatable in the journal well and a lubricating segment pressable against the journal, a T-shaped journal box lid seal portion integral with said base portion and having a cross pad against which the journal box lid is adapted to seal, a resilient mounting means overlying said base segment and said lid seal portion, and means adapted to secure said mounting means where it overlies said lid seal portion to the journal box thereby to anchor the lubricating device in journal lubricating and lid sealing position.

3. A journal lubricating device adapted to be mounted in a journal box through an end wall of which extends a journal and which has a well below the journal for holding a liquid lubricant, an access opening opposite the end wall, and a lid closing the opening, comprising a sheet of porous fibrous material having a base segment locatable in the journal well and an angularly upwardly extending lubricating segment pressable against the journal, a plurality of angular resilient biasing elements each having a leg attached to said base segment and a

leg attached to said lubricating segment for urging said lubricating segment firmly against the journal, a mounting strip overlying said base segment and positioned to extend longitudinally of the journal and thereunder, said base legs of said resilient biasing elements being secured to said mounting strip, a journal lid seal integral with said base segment, means securing said journal lid seal to the outer end of said mounting strip, and means adapted to secure said mounting strip adjacent its outer end and said lid seal to the front wall of the journal box so as properly to locate and anchor the lubricating device in the journal box.

4. A journal lubricating device adapted to be mounted in a journal box through an end wall of which extends a journal which has a well below the journal for holding a liquid lubricant, an access opening opposite the end wall, and a lid closing the opening, comprising a sheet of porous fibrous material having a base segment locatable in the journal well and an angularly upwardly extending lubricating segment pressable against the journal, a plurality of angular resilient biasing elements each having a leg attached to said base segment and a leg attached to said lubricating segment for urging said lubricating segment firmly against the journal, a mounting strip overlying said base segment and secured to said base legs of said resilient biasing elements, a journal lid seal integral with said base segment, said lid seal and said mounting member having coinciding slots formed therein and extending longitudinally of said mounting strip, and bolt means passing through said slots and adapted to secure said mounting strip and said lid seal to the front wall of the journal box so as properly to locate and anchor the lubricating device in the journal box.

5. A journal lubricating device adapted to be mounted in a journal box through an end wall of which extends a journal which has a well below the journal for holding a liquid lubricant, an access opening opposite the end wall, and a lid closing the opening, comprising a sheet of porous fibrous material having a base segment locatable in the journal well and an angularly upwardly extending lubricating segment pressable against the journal, a plurality of angular resilient biasing elements attached to said base segment and to said lubricating segment for urging said lubricating segment firmly against the journal, a mounting strip overlying said base segment and secured to said resilient biasing elements, a journal lid seal made of porous fibrous material, said mounting strip including a slotted anchor plate overlying said lid seal, said lid seal being slotted to coincide with said anchor plate slot, and bolt means passing through said slots and adapted to secure said mounting strip and said lid seal to the front wall of the journal box so as properly to locate and anchor the lubricating device in the journal box.

6. A journal lubricating device adapted to be mounted in a journal box through an end wall of which extends a journal which has a well below the journal for holding a liquid lubricant, an access opening opposite the end wall, and a lid closing the opening, comprising a sheet of porous fibrous material having a base segment locatable in the journal well and an angularly upwardly extending lubricating segment pressable against the journal, a plurality of angular resilient biasing elements attached to said base segment and to said lubricating segment for urging said lubricating segment firmly against the journal, a resilient mounting strip overlying said base segment and secured to said resilient biasing elements, a fillet seal and lubricator secured to the inner end of said mounting strip, and means adapted to secure said mounting strip adjacent its outer end to the front wall of the journal box so as properly to locate and anchor the lubricating device in the journal box and to hold said fillet seal and lubricator firmly against the inner face of the end wall of the journal box.

7. A journal lubricating device adapted to be mounted in a journal box through an end wall of which extends a journal which has a well below the journal for holding a liquid lubricant, an access opening opposite the end wall, and a lid closing the opening, comprising a sheet of porous fibrous material having a base segment locatable in the journal well and an angularly upwardly extending lubricating segment pressable against the journal, a plurality of angular resilient biasing elements attached to said base segment and to said lubricating segment for urging said lubricating segment firmly against the journal, a resilient mounting strip overlying said base segment and secured to said resilient biasing elements, a fillet seal and lubricator having a lubricant resistant facing, means securing said fillet seal and lubricator to the inner end of said mounting strip, and means adapted to secure said mounting strip adjacent its outer end to the front wall of the journal box so as properly to locate and anchor the lubricating device in the journal box and to hold said fillet seal and lubricator with its lubricant resistant facing firmly against the inner face of the end wall of the journal box.

8. A journal lubricating device adapted to be mounted in a journal box through an end wall of which extends a journal which has a well below the journal for holding a liquid lubricant, an access opening opposite the end wall, and a lid closing the opening, comprising a sheet of porous fibrous material having a base segment locatable in the journal well and an angularly upwardly extending lubricating segment pressable against the journal, a plurality of angular resilient biasing elements each having a leg attached to said base segment and a leg attached to said lubricating segment for urging said lubricating segment firmly against the journal, a resilient mounting strip overlying said base segment and positioned to extend longitudinally of the journal and thereunder, said base legs of said resilient biasing elements being secured to said mounting strip, a fillet seal and lubricator, means securing said fillet seal and lubricator to the inner end of said mounting strip, a journal lid seal, means securing said journal lid seal to the outer end of said mounting strip, and means adapted to secure said mounting strip adjacent its outer end to the front wall of the journal box so as properly to locate and anchor the lubricating device of the journal box and to hold said fillet seal and lubricator firmly against the inner face of the end wall of the journal box.

9. A journal lubricating device adapted to be mounted in a journal box through an end wall of which extends a journal which has a well below the journal for holding a liquid lubricant, an access opening opposite the end wall, and a lid closing the opening, the well having an inclined access wall terminating at the front opening, comprising a sheet of porous fibrous material folded to provide a base segment locatable in the journal well and a lubricating segment pressable against the journal, a T-shaped journal box lid seal portion adapted at least partially to overlie the inner face of the inclined well wall and having a cross pad against which the journal box lid is adapted to seal, a resilient mounting strip overlying said base segment and said lid seal portion, and a single bolt fitted with lock and sealing washers and a lock nut adapted to pass through coinciding openings in the inclined well wall and said mounting strip and lid seal portion securely to anchor the lubricating device in the journal box.
